UNITED STATES PATENT OFFICE

DANIEL J. SULLIVAN, OF GRANITEVILLE, MASSACHUSETTS

INSECT TRAP

Application filed March 12, 1931. Serial No. 522,045.

The object of this invention is to provide a very simple and inexpensive device whereby insects, more particularly mosquitoes, may be caught and prevented from harming human beings or doing other damage. The invention provides a light device which may be easily placed wherever desired and which will attract the insects and retain them within its walls so that they may be destroyed. The invention is illustrated in the accompanying drawings and will be herein-after first fully described and then more particularly defined in the appended claims.

In the drawings,

Figure 1 is a plan view of the partly completed trap as it is arranged for transportation or storage in quantities,

Fig. 2 is a transverse section of the trap as it is set up for use, and

Fig. 3 is a detail section on the line 3—3 of Fig. 2.

In carrying out the invention, there is provided a blank of cardboard or heavy paper or other similar material which will be sufficiently stiff to maintain its form after it has been arranged and set up as a trap. This blank comprises a main rectangular portion which is creased or scored along the transverse lines 1 so as to define side panels 2 and 3 and end panels 4 and 5, one end panel having a flap 6 formed along its side edge. Extending from opposite side edges of the side panels 2 and 3 are a top panel 7 and a bottom panel 8 which form the top and bottom, respectively, of the completed trap.

The panel 7 has marginal flaps 9 and 10 along its side and end edges, respectively, and the panel 8 has flaps 11 and 12 formed along its side and end edges, respectively. The panel 3 is constructed with openings 13 therethrough defined by radially extending webs 14 and a hub portion 15, and pivotally mounted upon the hub portion is a damper or valve 16 of similar form comprising radial spokes or webs and openings corresponding in area and form to the openings 13 through the panel 3. Secured upon the inner surface of the panel 3 over the said openings is a screen 16' of netting, and the pivot member 17 extends through the hub of the damper and the

hub portion of the panel and also through the screen 16', and washers or keeper plates 18 are provided against the outer surface of the damper hub and the inner surface of the screen, respectively, as will be understood upon reference to Fig. 2. The end panel 4 has an opening 19 formed therethrough, and upon the inner side of this panel, at the edges of this opening, are secured guards 20, consisting of strips of cardboard or other stiff material, which converge toward their inner ends so that a small opening will be left between said ends through which the insects may pass into the trap. In entering the trap, the wings of the insects will be folded, but when they attempt to escape from the trap, their wings will be outspread so that they will catch against the edges of the several guards and the egress of the insects will be thereby prevented. Upon the inner side of the panel 2 there is suspended a card or plate 21 carrying the bait. The bait is preferably blood, and it is applied to the bait holder by affixing to the holder a pad 22 of some absorbent material which has been dipped in the blood of slaughtered animals, the odor of which will attract mosquitoes and similar insects. The bait holder is provided near one end with a slot or opening 23 through which is engaged a hook 24 secured upon the inner surface of the side panel 2 adjacent the upper edge of the same so that the bait holder may be easily engaged thereon. The end panel 5 is equipped with a hook or similar device 25 which may be engaged through a strip of fly paper or similar adhesive material, indicated at 26, the purpose being to retain on this adhesive the insects which will fly against the same in their efforts to escape from the trap. During shipment and while the device is being set up for use, a cover 27 of non-adhesive material is held by the hook 25 so as to extend over the fly paper and prevent it adhering to the fingers or the clothing of the person who is engaged in folding and setting up the trap. The flap 6 is equipped with a tongue 28 of some light flexible material which may be readily bent into hook form, and the flap 11 is equipped with a tongue 29 of similar ma-

aterial. The side panel 2 is provided with a slit or narrow slot 30 near its lower edge, and with a similar slit or narrow slot 31 at its end edge, and is reinforced around both said slots or slits, as shown in Fig. 1.

In setting up the trap for use, the flaps 11 and 12 are turned upwardly at a right angle to the panel 8, and said panel 8 is turned or folded to a right angle with the side panel 10 3. The panels 4 and 5 are then folded to positions at right angles to the panel 3 so that they will abut the upturned flaps 12 and form the ends of the box which constitutes the trap. The side panel 2 is then folded so that 15 it will abut the flap 11, and the tongue 29 is engaged through the slit 30 and bent into hook form, as shown in Fig. 2, whereby the panel 2 will be held in proper relation to the bottom and ends of the box. The flap 6 is 20 folded so as to lie against the inner surface of the side panel 2, and the tongue 28 is inserted through the slit 31 and bent into hook form in the same manner as the tongue 29 is bent. At this stage of the proceeding, the 25 cover 27 may be removed from the hook 25 and the trap will then be completed by folding the top panel 7 over to the position shown in Fig. 2, with the flaps 9 and 10 fitting within the box and abutting the end panels and 30 the side panel 3, respectively.

The device may now be set upon any flat surface, or it may have applied to the panel 2, near the top of the same, a hook or other suspending device so that the trap may be 35 placed wherever its use may seem most desirable. The damper 16 is adjusted so that the openings 13 of the body of the trap will be exposed to such extent as judgment may dictate, and the odor of the blood upon the 40 pad 22 will then pass out through said openings 13 so as to attract the insects. As previously stated, the insects may pass through the opening 19 and enter the trap, but their efforts to escape will be frustrated by the 45 guards 20, and, in their efforts to escape, they will fly against the adhesive coated fly paper and be held thereon. At intervals, the top 50 of the trap may be lifted so that access may be had to the interior of the trap to renew the bait and the adhesive paper. In commercial use, extra bait holders with saturated pads will be supplied in sealed moisture-proof packages so that the bait holders may 55 be renewed indefinitely.

From the foregoing description, taken in connection with the accompanying drawings, it will be readily noted that I have provided an exceedingly simple and inexpensive device by the use of which mosquitoes and similar insects will be effectually trapped so that 60 they may be destroyed.

Having thus described the invention, I claim:

1. An insect trap comprising a box-like 65 structure having an ingress opening through

one end, guards on the inner surface of the box around said opening to prevent egress, the box being provided with openings through one side, a screen covering said openings, a damper mounted adjacent said openings and adapted to cover the same, and a bait holder suspended within the box. 70

2. An insect trap blank having side and end panels, a top panel and a bottom panel, one side panel having slits therethrough near its lower edge and near its free end edge, the top panel being foldable and provided at its edges with flaps adapted to fold between and abut the inner surfaces of the sides and ends thereof, the bottom panel having similar flaps, a tongue on one of said flaps engageable through the slit near the lower edge of one side panel, a flap on an end panel, a tongue on said flap insertible through the slit at the end of the mentioned side panel, the opposite end panel being provided with an ingress opening, a screened opening in one side panel, and a bait holder suspended on the opposite side panel. 75

In testimony whereof I affix my signature, 90
DANIEL J. SULLIVAN. [L. S.]
